CLAIM

We claim the ornamental design for a cartridge assembly of a beverage dispenser, as shown and described.

DESCRIPTION

FIG. 1 is a perspective view of the cartridge assembly of a beverage dispenser showing our new design;

FIG. 2 is a front view thereof;

FIG. 3 is a rear view thereof;

FIG. 4 is a right side view thereof;

FIG. 5 is a left side view thereof;

FIG. 6 is a top plane view thereof; and,

FIG. 7 is a bottom plan view thereof.

The broken lines in the drawings depict portions of the cartridge assembly of a beverage dispenser that form no part of the claimed design.
